UNITED STATES PATENT OFFICE.

WILLIAM E. BADGER, OF QUINCY, MASSACHUSETTS.

BALL-GOVERNOR FOR STEAM-ENGINES.

SPECIFICATION forming part of Letters Patent No. 278,387, dated May 29, 1883.

Application filed March 29, 1883. (No model.)

To all whom it may concern:

Be it known that I, WILLIAM EZRA BADGER, a citizen of the United States, residing at Quincy, in the county of Norfolk and State of Massachusetts, have invented certain new and useful Improvements in Ball-Governors for Steam-Engines; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to centrifugal ball-governors for regulating the speed of steam and other engines; and it consists in certain details of construction, as hereinafter described.

The drawings accompanying this specification represent, in Figure 1, a vertical cross-section of a governor containing my improvements. Fig. 2 is an end view of the shaft-support, hereinafter explained; and Fig. 3, a horizontal cross-section through the balls and valve-stem.

In said drawings, A represents the outer end of the valve-chest of the governor, the cap-plate of which chest is shown at A', such cap-plate, in the present instance, being horizontal, while the valve-stem connecting with the valve of such chest is shown at B, such stem being vertical.

Upon one side of the cap-plate A', I erect a curved standard or goose-neck, C, the top of which terminates in a vertical tubular head, D, the bore a of which is in axial alignment with the valve-stem B.

Within the bore of the head D is a rotary tubular shaft, E, which is driven by a miter-gear, F, secured to its lower end, below the bottom of the head D, this miter-gear revolving with and being driven by a twin gear, G, secured to the inner end of a horizontal shaft, H, which is journaled at such end in the base of the goose-neck C. The outer end of the shaft H is journaled in a hub, I, which constitutes part of a curved bracket, J, the hub upon the opposite end of such bracket being shown at K as loosely encircling a hub, L, upon the outer side of the goose-neck C.

The driving-pulley of the shaft H is shown at M as disposed between the arms of the bracket J. The bracket J is readily adjusted in position about the hub L, and the position of such bracket may be changed, with any change in the direction of the belt which drives the pulley M. Hitherto the pulley has been attached to one end of the shaft H, and the stress of the belt tends to wear opposite corners of the box or bearing; hence the shaft, after a short time, is thrown from its proper adjustment of ninety degrees with the shaft E, and the gears at once begin to cut each other. My object in adapting the bracket J to be changed in position relatively to the belt of the pulley M is to enable the outer end of the shaft H to resist to the best advantage the strains and thrusts due to the action of such belt, and insure a uniform wear upon the journals of such shaft.

To the upper end of the tubular shaft E, I affix oppositely-disposed arms N N, and to the extremity of each of these arms I pivot at its angle, by a horizontal pivot, b, a bell-crank lever, O, the upper and vertical arm of which is shown at c, and its horizontal arm at d, and I form each lever O with a third and pendent arm, e, which, in a state of rest, is parallel, or approximately so, to the axis of the valve-stem B. The arm e of each lever O is cylindrical, and has a peripheral screw-thread to enter a female thread cut axially in a ball, P, the two balls being of like size, and constituting, in connection with a bow-spring, the governing agency of the device. The said spring is shown at Q as yoke-shaped, with its ends pivoted, respectively, to the upper arms, c c, of the levers O, this spring, in common with governors of this class, tending to increase the gravitating effects of the balls P P.

Heretofore in governors of this class the position of the balls upon their suspensories has been unchangeable, the sensitiveness of the governor being adjusted by changing the tension of the spring. In my governor the stress or tension of the spring is uniform, and I adjust the sensitiveness of the governor by changing the positions of the balls upon their suspensory rods e e, which is readily accomplished by screwing them up or down upon such rods. In this manner the adjustment is

effected more perfectly and uniformly than by changing the stress of the spring, and the construction possesses certain mechanical advantages.

5 In lieu of screwing the balls P P upon the rods e, such rods may pass loosely through the balls and nuts screwed upon the rod upon opposite sides of each ball.

10 To enable the positions of the balls to be quickly and accurately adjusted to obtain any given number of revolutions of the engine, I engrave upon each rod e a scale of numerals, 1, 2, 3, &c., the relative positions of these numerals being such that when the balls are adjusted to correspond to them they indicate the number of revolutions the engine will make.

15 It will be seen that I employ balls of small size, and the pivots b b are sufficiently far apart to permit the suspensories e e of such balls to assume a vertical position, or approximately so, when at rest. For this reason the balls swing freely upon their supports and the governor is rendered very sensitive.

20 In ball-governors heretofore the suspensories of the balls do not drop to a vertical line, but are maintained at an angle, and the weight of the ball must be overcome more or less entirely when the steam-pressure is at its lowest point; hence the governor operates sluggishly. 25 30 at a time when it should be the most sensitive. In my governor the weight of the balls is neutral when the steam-pressure is lowest, for the reason, as before stated, that such balls swing freely from their supports, and their weight has not to be overcome until the steam-pressure increases considerably.

35 The valve-stem B, which has no rotary motion, passes upward loosely through the bore of the tubular shaft E, and a circular hub, R, which is supported in position by the arms d d of the levers O O, which are swiveled to it, this hub R being raised to its maximum height by the stress of the spring Q, combined with the gravity of the balls P, preferably aided by a coiled spring, S, which exerts its stress between said hub R and the top of the shaft E. The upper extremity of the valve-stem B passes

loosely through the center of the hub R, and is stepped in and secured to a disk, f, disposed upon the top of such hub, the disk f being thereby prevented from turning in rotary motion and constituting the point of suspension of the valve-stem. Upon the top of the disk f, I place a bearing-plate, h, which has a vertical stem, i, erected upon it, such stem playing in a tubular head forming the upper part of a short standard, j, erected upon or secured to the hub R, and rotating with the latter, the stem being secured within the head by a set-screw, k. The parts R, f, h, i, and j constitute means for compensating for wear upon the upper support of the valve-stem and for taking up any backlash that might otherwise result. As fast as any wear ensues between the hub R and disk f the screw k is loosened, the plate h pressed firmly down, and the screw tightened. 55 60 65

I claim—

1. In a ball-governor, a bent spring, Q, in combination with two levers, each having three arms, c, d, and e, the balls P on the lower arms, 70 e, of said levers, the pulley R, which engages with the inner arms, d, of said levers, and the valve-rod movable up and down with said pulley, substantially as set forth.

2. In combination with an adjustable gov- 75 ernor-ball and its actuating devices, a suspensory for said ball, having a scale of numerals marked upon it to indicate the number of revolutions of the engine, substantially as set forth.

3. The valve-stem B and the disk f, in which it terminates, in combination with the plate h, which bears against said disk, the rod i, rising from said plate, the hub R, held against the under side of said disk, the arm j, rigid with said hub, and having its upper end sleeved on 80 said rod i, and the screw k, which holds said arm and pin together, substantially as set forth.

In testimony whereof I affix my signature in presence of two witnesses.

WILLIAM EZRA BADGER.
